UNITED STATES PATENT OFFICE.

JAMES SLATER, OF NEW YORK, N. Y.

DESIGN FOR A PAPER-CUTTER.

SPECIFICATION forming part of Design No. 25,116, dated February 4, 1896.

Application filed December 12, 1895. Serial No. 571,950. Term of patent 7 years.

To all whom it may concern:

Be it known that I, JAMES SLATER, a citizen of the United States, residing at New York city, in the county and State of New York, have invented and produced a new and original Design for a Paper-Cutter, of which the following is a specification, reference being had to the accompanying drawing, forming a part thereof, which is a perspective view 10 of a paper-cutter embodying the features of my design.

The leading feature of the design consists in the paper-cutter shaped or longitudinally curved to simulate the sole, the instep, and the heel of a slipper or similar article of foot-wear.

The minor features of the design consists in the flat portion A, formed with a point at its outer end, and the arched portion B, carried upwardly and rearwardly over the heel-like support C, all portions of the design appearing intimately connected.

I claim—

The design for a paper-cutter, substantially as herein shown and described.

JAMES SLATER.
